(57) **CLAIM**

The ornamental design for a gear hook for sports baggage, as shown and described.

DESCRIPTION

FIG. 1 is a perspective view showing our new design.

FIG. 2 is a first side view.

FIG. 3 is a second side view, opposite the first side view.

FIG. 4 is a third side view, orthogonal to the first and second side views.

FIG. 5 is a fourth side view, opposite the third side view.

FIG. 6 is a fifth side view, orthogonal to the first and second side views and orthogonal to the third and fourth side views.

FIG. 7 is a sixth side view, opposite the fifth side view.

FIG. 8 is another perspective view, showing the first and sixth sides; and,

FIG. 9 is another perspective view, showing the second and sixth sides.

The dotted lines indicate portions of the gear hook for sports baggage that form no part of the claimed design.

1 Claim, 8 Drawing Sheets
